UNITED STATES PATENT OFFICE.

GARDNER B. GRAY, OF CRAFTON, PENNSYLVANIA.

SIGNAL MECHANISM.

SPECIFICATION forming part of Letters Patent No. 681,869, dated August 29, 1892.

Application filed May 6, 1890. Serial No. 716,777. (No model.)

To all whom it may concern:

Be it known that J. GARDNER B. GRAY, a citizen of the United States, residing at Crafton, in the county of Allegheny and State 5 of Pennsylvania, have invented or discovered certain new and useful Improvements in Signal Mechanism, of which improvements the following is a specification.

My invention relates to certain improvements in signaling mechanism, and has for its object a construction and arrangement of operating mechanism and controlling-circuits whereby the same signal may be employed as a "home" and "distant" signal, its movements from "clear" to "danger" and "caution" being effected automatically, but controlled by train movements.

In the accompanying drawings, forming a part of this specification, Figure 1 is a view 20 of the supporting-post or signal and showing the several positions of the semaphore-arm. Fig. 2 is a side elevation of the mechanism for operating the signal. Fig. 3 is a front elevation of same. Fig. 4 is a rear elevation. Fig. 5 is an enlarged sectional view of the upper portion of operating mechanism. Fig. 6 is an enlarged detail of the locking-block of the slot mechanism. Fig. 7 is a detail, the circuit-breakers controlled by the movements 30 of the signal. Fig. 8 is a sectional view on the line VIII VIII, Fig. 7. Fig. 9 is a diagrammatic view showing the circuits for operating the semaphore in a railway system, and Fig. 10 is a diagrammatic view showing 35 a modification in the circuits.

For convenience of illustration and also as being the preferable form of signal the improvements are described and shown in connection with the semaphore type of signal; 40 but as regards the broad terms of the claims the invention is not limited to such style of signals.

In the practice of the invention the blade 1 and its supporting-casting and spectacle-frame 2 are of the usual or any suitable construction and pivotally mounted on the tubular post 3 or other support in accordance 45 with the usual practice in the art. An arm 4 is secured to the pivotal shaft or pin 4^a, on 50 which the signal is secured, and the outer end of the arm is connected by separable members or parts to the signal-operating mech-

anism. This operating mechanism is preferably inclosed in a box or shell 3^a, forming the lower end or base of the signal-post, 55 through which pass the connections to the signal. While it is preferred that the parts or members connecting the signal with its operating mechanism and the slot mechanism for locking said parts or members together 60 should be constructed substantially as hereinafter described, any other suitable or known construction may be employed.

As shown in the drawings, especially in Fig. 5, the members connecting the signal with its 65 operating mechanism are formed by a sleeve 5 and a rod 6, fitting within the sleeve. Either 5 of these parts may be connected to the signal and the other to the operating mechanism, but it is preferred to connect the sleeve to the 70 signal by a short rod 7, as in such construction the sleeve forms a guide for the upper portion of the rod 6. The sleeve is provided with laterally-projecting wings 8, adapted to fit in guide-grooves formed in the inner faces of 75 the uprights 8^a of the frame of the machine. These wings are adapted to guide the sleeve in its vertical movement and also form an efficient means for connecting other parts of the mechanism, which are designed to move with 80 the sleeve, to the latter. In order to lock the sleeve and rod together, the sleeve is slotted at a suitable point along its length for the reception of locking-block 9, having an opening therethrough for the passage of the 85 rod, and also provided with a locking projection 10, adapted to be shifted into engagement with a notch or groove 11, formed in the rod 6. The distance between the inner 90 face of the locking projection and the opposite wall of the opening through the locking-block should be at least equal to the diameter of the rod 6, so that the rod may move freely through the block when the latter is shifted, as hereinafter described, to disengage 95 the tongue or projection 10 from the groove or notch in the rod. The block is shifted to engage the rod and held in such engagement by means of electromagnet 12, which is supported by a suitable frame or bracket 13, 100 carried by the sleeve 5. The armature 14 of this magnet is secured on one of the links 15, which are pivotally connected at or near the point of attachment of the armature. One

of these links has a pivotal seat in the frame or bracket 13, while the other link has its outer or free end loosely connected to a pair of links 16 at or near their pivotal connection 5 to each other. As shown in Fig. 5, the links 16 are arranged at an angle to links 15, and one of the former has a pivotal seat, as at 17, in the frame or bracket 13, while the outer or free end of the other link 16 has a bearing 10 against the locking-block 9. By reference to Fig. 5 it will be seen that the pivotal connection *a* of the links 15 is a little to one side of a line passing through the point of pivotal movement of the outer ends of these links, 15 so that when the magnet 12 is deenergized there will be a tendency on the part of the links to move out of line with each other and draw the armature away from the magnet. The point of pivotal connection of the links 20 16 is also a little to one side of a line passing through the axis of pivotal movement of the outer ends of the links, so that a pressure against the block 9 will be effective to turn the links 16 on their pivotal points, and this 25 movement will not be resisted to any material extent by the links 15 on account of the relative position of its pivotal point *a*. The weight of the link 16 will be sufficient to move the block 9 so that its tongue or projection 10 will engage the groove or notch in 30 the rod 6 when the latter is shifted to operative position, and the block will be held in such locking position on the energizing of the magnet 12. It will be readily understood 35 by those skilled in the art that this arrangement of toggle links or levers will afford a strong and secure fastening for the locking-block with a minimum expenditure of power by the electromagnet 12. It will also be 40 readily understood by those skilled in the art that this arrangement of toggle links or levers can be employed with or applied to other forms of locks or latches for holding the two parts or members of a signal connection in 45 operative relation to each other. The locking-block 9 is shifted so as to remove the tongue or projection 10 out of engagement with the notch or groove in the rod 6 by means of the weight of the sleeve and the 50 signal, the bearing-faces of the tongue 10 being inclined or beveled, as at *c*, and the walls of the groove or notch being similarly inclined, as clearly shown in Fig. 5, so that the weight of the signal, which is constructed to 55 have a bias to danger position, will be sufficient to effect the unlocking movement of the block 10.

The shifting of the signal to caution and clear positions is preferably effected by means 60 of an electric motor 18, and the armature-shaft is operatively connected by a train of gearing or any other suitable form of transmitting mechanism to the shaft 19, on which is secured the pinion 20. The teeth of this 65 pinion are adapted to engage a series of teeth formed on the rod 6 at or near its lower end, so that by the rotation of the pinion the rod

may be raised to shift the signal to caution and clear positions. In order to permit the rod 6 to move down after the signal has gone to "danger" without any reversal of the motor and its train of gearing, some of the teeth on the pinion 20 are removed, so that when the untoothed or mutilated portion of the pinion comes opposite the rack on the lower end 75 of the rod 6 the latter will be free to drop.

In order to relieve the train of gearing and motor from the weight of the signal when in clear and caution positions and also to prevent any tendency to a reversed movement of the motor by the weight of the signal, the pawls 21 21^a are pivotally mounted upon brackets 22, secured to the uprights of the frame of the machine in such manner or at such points that the pawls will project into 85 the path of movement of the block 9 when shifted to locking position. These brackets are so located vertically on the frame that when the signal has been moved down to caution or clear position the projecting end of the block 9 will have moved just above one or the other of these pawls, which will drop under the projecting end of the block, and thereby prevent any downward movement of the sleeve so long as the block is held in locked 95 or operative position. It is preferred to so incline or bevel the portions of the block 9 and pawls 21 21^a, which bear against each other, that the weight of the signal and sleeve will have a tendency to move the block to unlocking position, and thereby reinforce the action of the inclined faces on the tongue 10 and the walls of the notch or groove in the rod 6.

As it is possible in the construction of automatic signals now in use for the signal to be moved from danger position while its operating mechanism is in danger position, and thereby cause the signal to give a wrong indication, it is preferred to employ a lock for holding the signal in danger and caution positions so long as track conditions require such positions on the part of the signal. To this end an arm 23 is pivotally mounted on the frame of the machine in such position that a hook or projection on its end will engage 110 notches 24 on the sleeve 5 when the signal is in danger or caution position. The hook is shifted to engage these notches by a spring 25, mounted on a bracket 26, secured to the uprights of the machine, and is held in operative position or one in which the sleeve will be free to move by a magnet 27, whose circuit will be hereinafter described, and is controlled by train movements along the section 120 guarded by the signal.

In order to prevent any overrunning of the signal-shifting mechanism when the circuit of the motor is broken, a brake-drum 28 is secured on the armature-shaft or the shaft of any of the parts of the train-gearing driven 130 by the armature, and a shoe 29 is secured to an arm 30, which is pivotally mounted in such relation to the brake-drum that when free to move the shoe will be forced against the drum.

The braking movement of the shoe is preferably effected by means of a weight 31 on an arm 32, projecting at an angle from the arm 30. The brake-shoe is held away from the drum by means of electromagnets 33, which are included in the circuit of the motor, so that said brake will be applied instantly on the rupture of the circuit.

In order to prevent shocks to the mechanism when the signal is shifted, a cylinder 70, having a controlled outlet and inlet, is secured to the bracket 13 and a piston 71 is arranged within the cylinder, the stem 72 of the piston being secured to the frame of the machine.

The motor-circuits and the circuit for energizing the slot-magnet are controlled by or in accordance with the movements of the signal, and to this end circuit-breaking mechanisms 34, 35, and 36 are so arranged with reference to a movable part of the switch-operating mechanism or the signal as to be opened and closed in a certain predetermined order, as hereinafter described. Any suitable form of construction of circuit-breaker may be employed—such, for example, as that shown in Figs. 1, 4, 7, and 8. These consist of spring-plates mounted on a block of insulating material and arranged upon the frame of the machine, so as to lie in the path of a projection or rib 37, carried by the sleeve 5. The springs forming the circuit-breakers 34 and 35 are so constructed and arranged that when free to move they will bear against each other and complete the circuit, which will be broken, as hereinafter described, by the rib or projection 37 forcing one spring of each circuit-breaker from the other. The circuit-breaker 36 has its springs so constructed that they will normally stand apart to maintain an open circuit, but are adapted to be closed against each other by the rib or projection 37.

As is the usual practice, the rails between adjacent sections are constructed to form a circuit, the rail of each section being insulated from those of the adjoining sections, and each track-section X, Y, Z has connected therewith a relay 38 and a track-battery 39. It is the general practice in automatic signaling to arrange the track-circuits and the signal-operating mechanism controlled thereby, so that the signal at the entrance of each section will be shifted to danger position as soon as the front pair of wheels of the engine or car passes the insulating-point, so that only the trainmen at the front end of the train have any knowledge of the position of the signal prior to the entrance of the train onto the section. This is especially the case with long freight trains and where the signal is located on a curve. In order to afford all the trainmen on each train knowledge of the position of the signal prior to the entrance of the train on the section, suitable means are provided to maintain the signal in its clear position until the last pair of wheels of the train have entered upon the section guarded

by such signal. This is considered the better practice, as it is sufficient for the engineer to know that the section upon which he is about to enter is clear, and this practice also affords a check upon the front trainmen, as the rear trainmen will know if they do not see the signal go to "danger" that it is probable that the engineer has run by the signal when in danger position. To this end each main section is subdivided into two sections, as X x, Y y, and Z z, the subsections x, y, and z being located at the entrance of each block-section. This subsection has one rail connected to one pole of a battery whose circuit is formed by the relay 41, wire 42, circuit-breaker 36, wire 43 to the other rail of the subsection. It will be observed that this is a normally open section and will not be closed until a pair of wheels enters upon the section. By the closure of this circuit the relay is energized and its armature 44 is so shifted as to close the circuit consisting of wires 45 and 46, battery 47, slot-magnet 12, wire 48, armature 53^a of relay 38 at the next signal in advance, wires 48^a and 51 to armature 44. The rib or projection 37 is so located as to hold the circuit-breaker 36 closed while the signal is in clear and caution positions, so that the circuit formed in part of the subsection x will remain closed as long as any pair of wheels of the train is upon such section, which is made of a length a little greater than the distance between any two pairs of wheels of a train. As long as the circuit of this subsection is closed, the circuit above described, through the slot-magnet 12, will remain closed and the signal in clear or caution position. A second circuit of the slot-relay 12 consists, starting from the battery 47 of the magnet 12, wire 48, armature 53^a of relay 38 at the next signal in advance, wires 48^a, 51, and 52, armature 53 of track-relay 38 or track-section X, wires 54 and 46 to battery. As long as the relays 38 of sections X and Y are energized, the armatures 53 and 53^a will be held against their front contacts, maintaining the slot-circuit in closed position; but as soon as a train enters upon section X relay 38 will be cut out, thereby permitting the armature 53 to move away from its contact and open the main slot-circuit; but so long as any pair of wheels is upon the subsection x the shunt-circuit through the slot will be held closed and the signal "clear." As soon as the last pair of wheels passes off subsection x the relay 41 will become de-energized and the shunt-circuit broken, so that the slot-magnet 12 is cut out, permitting the locking-block 9 to move out of engagement with the rod 6 and the signal to move to danger position. By the movement of the signal to danger position the circuit-breaker 36 will be opened and the circuit-breakers 34 and 35 closed. These circuit-breakers form a part of the motor-circuits, one of which consists, starting from the battery 55 of the wire 56, armature 53^a of re-

lay 38, wire 57, brake-magnets 33, catch-magnet 27, motor 18, wire 58, circuit-breaker 35, wire 59 to battery. This circuit may properly be termed the "caution-circuit," as by its closure the signal is shifted from danger to caution positions. The other circuit for shifting the signal from caution to clear positions consists, starting from the battery 55 of the wire 56, armature 53^a of relay 38, wire 57, 10 brake-magnet 33, catch-magnet 27, motor 18, wire 58, circuit-breaker 34, wire 60, armature 49 or relay 50, wire 59 to battery. It will be observed that the circuit-breaker 35 is closed while the signal is in danger position, but it 15 will be opened by the rib or projection 37 so soon as the signal reaches caution position. The circuit-breaker 34 of the signal-clearing circuit is so located as to be in closed position so long as the signal is in danger and 20 caution positions, but it will be opened by the rib or projection 37 so soon as the signal reaches clear position. Both of these motor-circuits are controlled by the track-relay 38, so that as long as such track-relay is deenergized 25 the motor-circuits will remain open, and by the opening of such circuits the brake-magnet is deenergized, permitting the operation of the brake, and the catch-magnet 27 is also deenergized, permitting the shifting 30 of the catch 23 by the spring 25 into engagement with one or the other of the notches 24 in the sleeve 5. The signal-clearing circuit is also controlled by the relay 50, the circuit of which consists, starting from the relay of 35 the wire 61, armature 53^a at station Y, wire 62, battery 63, wire 64, relay 50. As the circuit for clearing the signal at section X is dependent or controlled by the relay 50, whose circuit is controlled by the track-relay 38 of 40 the section Y, the signal-controlling section X cannot be cleared until the relay 38 of section Y becomes energized, and this cannot occur as long as a train is upon the section Y.

As the circuits for the motor are the same 45 at each station, it will be readily understood that the signal 1^a controlling section Y will go to danger position as soon as a train enters upon such section, and as the caution-circuit of the signal of section X is entirely independent of any adjacent section the signal 1 cannot be shifted beyond caution position so long as section Y is occupied.

It will be observed that the main slot-circuit of section X is controlled by relay 38 of 55 section Y and also the signal-clearing circuit through the relay 50. Hence in case of a break in the track-circuit of section Y, as by the opening of a switch or the removal of a rail, the circuit of the slot of section X will 60 be broken, permitting the signal 1 to go to "danger;" but the slot-magnet 12 will be immediately reenergized, as the break in the circuit of relay 50 will permit armature 49^a to be moved against its back stop, thereby 65 closing a circuit consisting of battery 47, slot-magnet 12, wire 48, back-stop armature 49^a, wires 51 and 52, armature 53, wires 54 and 46

to battery. The movement of the signal to "danger" permits the closure of the motor-circuits, so that the signal will be shifted from 70 "danger," but cannot go beyond "caution" as the signal-clearing circuit was broken by the movement armature 49 of relay 50 from its front contact.

By reference to Figs. 2 and 9 it will be seen 75 that when the rod 6 is raised the teeth on the rod 6 are engaged by only a few of the teeth of the mutilated pinion 20 and those adjacent to the mutilated portion. As soon as the slot magnet is deenergized the sleeve 5 drops 80 along the rod 6, carrying with it the slot mechanism. As soon as the motor is energized the pinion 20 will be rotated in the direction of the arrow and its teeth disengage from the rack of the rod 6, which will drop 85 sufficiently far to bring the groove or notch therein in line with the locking-block 9. As the slot-magnet is energized simultaneous with the closing of the motor-circuit, the block 9 will be shifted so as to lock the sleeve and 90 rod together as soon as the groove or notch in the latter comes into line with the block. By the continued rotation of the pinion 20 the rod 6 and with it the sleeve and signal will be shifted to caution position, where 95 the circuit-breaker 35 will be opened, opening the motor-circuit. On the deenergization of the magnet 27 the catch 23 will be shifted into engagement with the lower one of the notches 24, thereby so locking the 100 sleeve 5 that the signal cannot be shifted from caution to clear positions, but will not interfere with its further movement to danger position. When the signal moves to danger position in the manner described, the catch 105 23 will engage the lower one of the notches 24 and hold the signal in rear position, the circuit of the magnet 27 being broken.

In the arrangement of circuits shown in Fig. 10 the shunt circuit-through slot-magnet 110 12 is omitted and the circuit of this magnet is formed, starting from the battery 47, by wire 73, magnet 12, wire 74, front and back stops of armature 49 of relay 50, wire 75, stop of armature 76 of relay 77 and wire 78 to 115 battery. Relay 77 is included in a circuit consisting, starting from battery 79 of wire 80, relay 77, wire 81, armature 53 of track-relay 38, and wire 82 to battery, so that the slot-circuit through magnet 12 will be broken 120 while a train is on main track-section X, provided the circuit through relay 41 is not completed by a pair of wheels on subsection x. The closing of the circuit through relay 41 will hold the armature 44 of relay 41 in such position as to lock the armature 76 against its front stop, thereby preventing such movement of the armature as will break the circuit through slot-magnet 12, although relay 77 may be deenergized, as stated. Thus it will 125 be understood that by means of interlocking armatures and suitable circuits the signal will be held in clear position until the last pair of wheels of a train passes off of subsection x.

In lieu of extending the circuit of the slot-magnet 12 to the track-relay 38 of section Y in advance, so that the signal 1 be shifted to "caution" in the manner described in case 5 a switch is opened or a rail removed in section Y, this slot-circuit may be controlled entirely by relay 50, as shown in Fig. 10. The circuit of relay 50 consists of wire 61, armature 53^b of relay 38 of section Y, wire 62, battery 63, and wire 64 to relay. It will be observed that as long as relay 38 of section Y is energized the circuit of relay 50 will be held closed, so that the circuit of slot-magnet will be held closed by armature 49 bearing 15 against its front stop. As soon as relay 50 is deenergized the circuit of slot-magnet 12 will be broken, permitting signal to go to "danger;" but the circuit of slot-magnet 12 will be immediately closed by the armature 49 bearing against its back stop, so that the signal 20 will be shifted to "caution" in the manner described.

I claim herein as my invention—

1. In a signal mechanism, the combination 25 of a signal having a bias to danger position, electrically-controlled mechanism for locking the signal at clear position, and two independent circuit-breakers controlled by train movements for controlling the signal-locking mechanism, said circuit-breakers being simultaneously operative to release the signal from clear position, substantially as set forth.

2. In a signal mechanism, the combination 35 of a signal having a bias to danger position, electrically-controlled mechanism for locking the signal at clear position, main and shunt circuits for such mechanism and independent track-circuits controlling the main and shunt 40 circuits whereby the signal is released only on the simultaneous shifting of both circuits, substantially as set forth.

3. In a signal mechanism, the combination 45 of a signal having a bias to danger position, electrically-controlled mechanism for holding the signal at clear position, main and shunt circuits for such mechanism, one of said circuits being normally open and the other normally closed, and independent track-circuits controlling the main and shunt circuits and 50 adapted to reverse the normal conditions of said main and shunt circuits and thereby release the signal from clear position, substantially as set forth.

4. In a signal mechanism, the combination 55 of a signal having a bias to danger position, electrically-controlled mechanism for holding the signal at clear position, main and shunt circuits for such mechanism, a circuit-breaker in the shunt-circuit adapted to be shifted on 60 the shifting of the signal, and independent track-circuits adapted to reverse the normal conditions of said main and shunt circuits and thereby release the signal from clear position, substantially as set forth.

5. In a signal mechanism, the combination 65 of a signal automatically movable to danger position, mechanism for shifting the signal to

caution and clear positions and electrically-controlled means for holding the signal in said positions, substantially as set forth.

6. The combination of a vertically-movable rod having a toothed portion, a sleeve movable along said rod, a signal-arm operated by said sleeve, an electrically-operated lock adapted to connect said rod and sleeve, a mutilated pinion engaging said rack, and a motor for operating the pinion, substantially as set forth.

7. The combination of a rod, a sleeve movable along said rod, a semaphore connected 80 to said sleeve, an electrically-operated lock adapted to connect said rod and sleeve, an electrically-controlled motor and a series of make-and-break mechanisms included in the controlling-circuits of the motor and controlled by the movement of the signal, substantially as set forth.

8. The combination of a movable rod, a sleeve movable along said rod, a semaphore connected to said sleeve, a block movable 90 transversely of said sleeve and adapted to engage a groove or notch in said rod, and an electrically-operated arm adapted to engage said block and move it into engagement with said rod, substantially as set forth.

9. In a signal mechanism, the combination 95 of a signal, means for shifting said signal, a connection between the signal and the shifting means consisting of two separable parts or members, a lock for detachably connecting said parts or members, two pairs of pivotally-connected levers arranged at an angle to each other, an electromagnet for shifting one pair of levers, thereby causing the other to shift the lock, substantially as set forth.

10. The combination of a movable rod, a sleeve movable along said rod, a semaphore connected to said sleeve, a block movable transversely of said sleeve and adapted to engage a groove or notch in said rod, a toggle-lever adapted to engage said block and move it into engagement with said rod, and an electromagnet for shifting the toggle-lever, substantially as set forth.

11. The combination of a movable rod, a 115 sleeve movable along said rod, a semaphore connected to said sleeve, a block movable transversely of said sleeve and adapted to engage a groove or notch in said rod, a toggle-lever for shifting said block, a second toggle-lever connected to said first-mentioned toggle-lever, and a magnet adapted to operate said second toggle-lever, substantially as set forth.

12. The combination of a vertically-movable 125 rod, a slidable sleeve on said rod, a semaphore connected to said sleeve, an electrically-operated block movable transversely of said sleeve and adapted to engage a groove or notch in said rod, and one or more detents 130 on the frame adapted to engage said block, substantially as set forth.

13. The combination of a vertically-movable rod, a slidable sleeve on said rod, a sema-

phore connected to said sleeve, and an electrically-controlled latch on said frame adapted to engage said sleeve, substantially as set forth.

5 14. The combination of a vertically-movable rod, a slidible sleeve on said rod, having one or more notches therein, a semaphore connected to said sleeve, and an electrically-

controlled latch adapted to engage said notches, substantially as set forth.

In testimony whereof I have hereunto set

my hand.
